UNITED STATES PATENT OFFICE.

ILDEBERTO J. ALVAREZ, OF NEW YORK, N. Y.

DESIGN FOR A PENDANT MIRROR.

Application filed May 29, 1923. Serial No. 6,315. Term of patent 3½ years.

To all whom it may concern:

Be it known that I, ILDEBERTO J. ALVAREZ, a citizen of Cuba, residing at New York, in the county of New York and State of New York, have invented a new, original, and ornamental Design for a Pendant Mirror, of which the following is a specification, reference being had to the accompanying drawing, forming a part thereof.

I claim:

The ornamental design for a pendant mirror, as shown.

ILDEBERTO J. ALVAREZ.
